UNITED STATES PATENT OFFICE.

EDWIN S. PHILIPS, OF KENNETT SQUARE, PENNSYLVANIA, ASSIGNOR TO THE AMERICAN ROAD MACHINE COMPANY, OF KENNETT SQUARE, PENNSYLVANIA, A CORPORATION OF PENNSYLVANIA.

MOUNTED SCREEN-BIN.

No. 810,219.

Specification of Letters Patent.

Patented Jan. 16, 1906.

Application filed August 15, 1905. Serial No. 274,264.

To all whom it may concern:

Be it known that I, EDWIN S. PHILIPS, a citizen of the United States, residing at Kennett Square, county of Chester, and State of Pennsylvania, have invented a new and useful Improvement in Mounted Screen-Bins, of which the following is a full, clear, and exact description, reference being had to the accompanying drawings, which form a part of this specification.

My invention relates to portable or mounted screen-bins adapted for handling crushed stone.

Mounted screen-bins consist, essentially, of a frame mounted on axles, the bin proper, mounted on the frame, having pockets or compartments, a screen above the bin to receive the crushed stone, having sets of perforations of different sizes adapted to assort the stone and deliver the same into the several pockets, and chutes leading from the pockets to deliver the assorted stone from the pockets to wagons.

The object of the invention is to provide means to raise or lower the bin, and with it the screen, and at the same time raise or lower the screen relatively to the bin, thereby enabling the center of gravity of the wagon to be lowered when the outfit is not in use and it is being transferred from place to place, while enabling the screen and bin to be placed in the most advantageous positions when in use.

Figure 1 is a side elevation of the machine with the bin-frame and screen-frame raised. Fig. 2 is an end elevation of same. Fig. 3 is a vertical section on the line 3 3 of Fig. 2, on an enlarged scale. Fig. 4 is a transverse section, also enlarged, on the line 4 4 of Fig. 1. Fig. 5 is a similar section on the line 5 5 of Fig. 1. Fig. 6 is a detail side elevation of a modified way of securing the main operating-chain. Fig. 7 is a front elevation of same. Fig. 8 is a perspective view showing another modified form of raising and lowering mechanism.

a a are the wheels on which the carrying-frame is mounted. The carrying-frame consists of the side bars *b*, the uprights or posts *c*, the cross-bars *d*, and the braces *e*, bolted to the lower cross-bars and the corner-posts.

Within the carrying-frame is the bin-

frame, adapted to move up and down within the carrying-frame in telescopic fashion. The bin-frame consists of a box *f*, the upright corner-posts *g* of which extend above the box.

Within the bin-frame is the screen-frame, which is adapted to move telescopically up and down within the bin-frame.

The screen-frame is composed of the posts *h*, the side bars *i*, and the cross-bars *j*. The rotary screen *k* is supported on the frame in the usual manner.

Extending lengthwise through the bin-frame and turning in bearings in the front and rear walls thereof is the shaft *l*. The following mechanism, actuated and controlled by the shaft *l*, is provided both at the front and rear: *m* is a hand-wheel secured to shaft *l*. *n* is a worm on shaft *l*. *o* is a shaft running crosswise and turning in bearings on the bin-frame. *p* is a worm-wheel fast on the shaft *o* and engaging the worm *n*. *q q* are sprocket-wheels or pulleys on the shaft *o*. About each sprocket-wheel *q* extends a sprocket-chain *r*, one end of which is attached to the upper cross-bar of the outside carrying-frame, while the other end is attached to the hooked end of a rod *s*, secured to one of the posts of the screen-frame. Turning in bearings in the upper projecting ends of the corner-posts of the bin-frame is a cross-shaft *t*. *u u* are sheave-pulleys on the shaft *t*. About each pulley *u* extends a chain *v*, one end of which is attached to the upper cross-bar of the outside carrying-frame, while the other end is attached to one of the posts of the screen-frame.

The apparatus is shown with the bin-frame and screen-frame raised to their extreme uplifted position, which is their normal position when in operation.

To drop the bin-frame and screen-frame, one or both of the hand-wheels *m* are turned, thereby, through the medium of the worms *n*, worm-wheels *p*, and shafts *o*, causing the sprocket-wheels *q* to climb down the sprocket-chains *r*, thus lowering the bin-frame. As the bin-frame moves down the pulleys *u*, being supported thereon, descend with the bin-frame, and as the chains *v*, which pass over the pulleys *u*, are secured at one end to the carrying-frame and at the other end to the

corner-posts of the screen-frame the screen-frame is lowered relatively to the bin-frame. At the same time the sections of the chains *r* between the pulleys *q* and rods *s* are shortening, thus as the screen falls maintaining constant the distance between the points of attachment of the chains. The turning of the hand-wheel is continued until the bin-frame rests on the carrying-frame, at which time 10 the screen-frame will rest on the floor of the bin-frame. All the working parts are thus brought to a low position, this lowering of the center of gravity rendering the bin very stable and enabling it to be readily hauled 15 from place to place.

To elevate the bin-frame and screen-frame to their normal working positions, one or both of the hand-wheels *m* are turned, thereby through the medium of the worms *n*, 20 worm-wheels *p*, and shafts *o* causing the sprocket-wheels *q* to climb up the sprocket-chains *r*, thus elevating the bin-frame. The pulleys *u*, being supported on the bin-frame, rise with the latter, and as the chains *v*, which 25 pass over the pulleys *u*, are secured at one end to the carrying-frame and at the other end to the corner-posts of the screen-frame the pulleys *u* pull up the ends of the chains secured to the screen-frame, and thus elevate 30 the screen-frame relatively to the bin-frame. At the same time the sections of the chains *r* between the pulleys *q* and rods *s* are lengthening, thus permitting the screen to rise, as described.

35 When the bin is raised for work, the weight of the bin and its contents is supported by means of cross-pieces *w*, resting on brackets *x*, secured to the posts of the carrying-frame, and the weight of the screen is supported by 40 means of a pin or bolt 10, passed through the post of the bin and the post of the screen-frame. The chain and raising mechanism are thereby relieved from strain when the bin and screen are in use.

45 *y* designates the usual legs or supports, hinged to the side bars of the carrying-frame. These legs are swung into position to take the weight of the load when the screen-bin is in operation. They are held in this position by 50 hooked rods *z*, pivoted to the side bars of the carrying-frame and engaging pins 7 on the supporting-legs. When the bin-frame and screen-frame are lowered preparatory to moving the bin on the road, the legs *y* are swung into an upright position above the side bars of the supporting-frame and are held in this 55 position by the hooked rods *z*.

The bin proper may be provided with any desired number of compartments, for each of 60 which there is a discharge-opening, in front of which is a hinged discharge-chute 8, provided with raising and lowering tackle 9.

The partitions 11 in the bin should be hinged at 12, so that they can be folded down 65 to permit the screen-frame to descend.

In the modifications shown in Figs. 6 and 7 the rods *s* are removed and drums or pulleys 20 substituted for the sprocket-wheels or pulleys *q*, each chain or cable *r* being coiled about its corresponding drum and secured thereto. To raise the bin-frame, the drums are turned by means of the hand-wheel and intermediate connections, so as to wind chains *r* about the drums. To lower the bin-frame, the drums are turned so as to unwind 75 the chains.

In the modification shown in Fig. 8 in place of the sprocket-wheels *q*, chains *r*, rods *s*, shafts *t*, pulleys *u*, and chains *v* the following construction is provided: Secured to 80 each corner-post of the carrying-frame is a bracket 30, having a rack 31. Secured to the shaft *o* are pinions 32, engaging the racks 31 and a sprocket-wheel 33. Turning in bearings in the upper projecting ends of the 85 corner-posts of the bin-frame is a cross-shaft 36, on which are secured the sprocket-wheel 35 and the pinions 37. A sprocket-chain 34 passes around sprocket-wheels 33 and 35. Secured to the corner-posts of the screen- 90 frame are the racks 38, engaging the pinions 37. To raise the bin-frame and screen-frames, the shafts *o* are turned by means of the hand-wheel and intermediate connections, so as to cause the pinions 32 to climb 95 up the racks 31, thus elevating the bin-frame. At the same time the shafts 36 through the sprocket-wheel and chain connections described are turned so as to cause the pinions 37 to climb down the racks 38, thereby elevating the screen-frame. A reverse rotation of the shafts causes the bin-frame and screen-frame to descend, as will be readily understood.

Having now fully described my invention, 100 what I claim, and desire to protect by Letters Patent, is—

1. In a mounted screen-bin, the combination, with the carrying-frame, of a bin-frame and a screen-frame, each movable vertically with relation to each other and the carrying-frame, and means for simultaneously raising or lowering the bin-frame and screen-frame.

2. In a mounted screen-bin, the combination with the carrying-frame, of a bin-frame and a screen-frame and means to move the screen-frame vertically a determinate distance relatively to the carrying-frame and simultaneously therewith the bin-frame vertically a less distance.

3. In a mounted screen-bin, the combination with the carrying-frame, of a bin-frame movable vertically in guides in the carrying-frame, a screen-frame movable vertically in guides in the bin-frame, and means for simultaneously moving the bin-frame and screen-frame vertically at different speeds relatively to the carrying-frame.

4. In a mounted screen-bin, the combination with the carrying-frame, of a bin-frame

and a screen-frame each movable vertically with relation to each other and the carrying-frame, a shaft extending longitudinally of the bin-frame and supported thereon, a hand-wheel at each end thereof, and connections from the shaft to both the bin-frame and the screen-frame for elevating or lowering them simultaneously.

5. In a mounted screen-bin, the combination with the carrying-frame, of a bin-frame and a screen-frame each movable vertically with relation to each other and the carrying-frame, cross-shafts one at each end of, and supported on, the bin-frame, means to turn 15 said shafts and connections from the shafts to both the bin-frame and the screen-frame for elevating or lowering them simultaneously.

6. In a mounted screen-bin, the combination with the carrying-frame, of a bin-frame and a screen-frame each movable vertically with relation to each other and the carrying-frame, pulleys supported on the bin-frame, chains one end of each connected to the 25 screen-frame and the other end to the carrying-frame and between its ends engaging its corresponding pulley, and means to raise or lower the bin-frame, thereby, through the said chains and pulleys, simultaneously raising or lowering the screen-frame relatively to the bin-frame.

7. In a mounted screen-bin, the combination with the carrying-frame, of a bin-frame and a screen-frame each movable vertically 35 with relation to each other and the carrying-frame, pulleys supported on the bin-frame, chains one end of each connected to the screen-frame and the other end to the carrying-frame and between its ends engaging its 40 corresponding pulley, other chains secured at one end to the carrying-frame, cross-shafts turning in bearings on the bin-frame, pulleys on the cross-shafts engaging the last-named chains respectively, and means to turn said 45 shafts.

8. In a mounted screen-bin, the combination with the carrying-frame, of a bin-frame and a screen-frame, each movable vertically with relation to each other and the carrying-frame, chains connected to the screen-frame, 50 pulleys supported on the bin-frame and engaged by the respective chains, other chains connected to the screen-frame, other pulleys supported on the bin-frame and engaged by the last-named chain respectively, and means to turn the last-named pulleys.

9. In a mounted screen-bin, the combination with the carrying-frame, of a bin-frame and a screen-frame each movable vertically 60 with relation to each other and the carrying-frame, chains connected at one end to the screen-frame and at the other end to the carrying-frame, pulleys on the bin-frame about which the respective chains extend, other 65 chains connected at one end to the screen-

frame and at the other end to the carrying-frame, other pulleys on the bin-frame about which the last-named chains respectively extend, and means to turn the last-named pulleys.

10. In a mounted screen-bin, the combination with the carrying-frame, of a bin-frame and a screen-frame each movable vertically with relation to each other and the carrying-frame, chains connected to the 70 screen-frame, pulleys supported on the bin-frame and engaged by the respective chain, other chains connected to the screen-frame, other pulleys supported on the bin-frame and engaged by the last-named chains respectively, shafts to which the last-named pulleys are secured, a worm-wheel secured to each shaft, a driving-shaft, and a worm on the driving-shaft engaging each worm-wheel.

11. In a mounted screen-bin, the combination with the carrying-frame, of a bin-frame and a screen-frame each movable vertically with relation to each other and the carrying-frame, chains connected at one end 80 to the screen-frame and at the other to the carrying-frame, pulleys on the bin-frame about which said chains respectively extend, other chains connected at one end to the screen-frame and at the other end to the carrying-frame, other pulleys on the bin-frame about which the last-named chains respectively extend, a shaft, a hand-wheel thereon, worms on the shaft, worm-wheels driven by the worms, and shafts to which the worm-wheels and last-named pulleys are secured.

12. In a mounted bin, the combination with the screen-frame, the upright posts of the carrying-frame having guides, the upright posts of the bin-frame vertically movable in said guides and having guides in which the screen-frame is vertically movable, raising mechanism for simultaneously lifting the bin-frame on the guiding-posts of the carrying-frame and the screen-frame on the 105 guiding-posts of the bin-frame, a support engaging the carrying-frame and bin-frame for holding the latter in its elevated position, and a support engaging the bin-frame and screen-frame for holding the latter in its elevated position, thereby relieving the strain on the raising mechanism.

13. In a mounted screen-bin, the combination with the carrying-frame, of a bin-frame telescoping within the carrying-frame, 120 a screen-frame telescoping within the bin-frame, a shaft extending lengthwise of the bin-frame and extending beyond the ends thereof, and turning in bearings thereon, hand-wheels one at each end of the shaft, 125 worms on the shaft one near each hand-wheel, worm-wheels one engaging each worm, a shaft at each end of the bin-frame and extending crosswise thereof and turning in bearings thereon, a worm-wheel on each 130

cross-shaft engaging the corresponding worm, two pulleys on each cross-shaft, rods, one secured to each corner of the screen-frame, chains, each secured at one end to its 5 corresponding rod and at the other end to the carrying-frame and between its ends engaging its corresponding pulley, a second cross-shaft at each end of the bin-frame, two pulleys thereon, and chains, each secured at one 10 end to the screen-frame and at the other end

to the carrying-frame and between its ends engaging the corresponding pulley.

In testimony of which invention I have hereunto set my hand, at Philadelphia, on this 4th day of August, 1905.

EDWIN S. PHILIPS.
